UNITED STATES PATENT OFFICE.

ERASTUS E. WINKLEY, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING ON SHOE-WELTS.

1,242,504.

Specification of Letters Patent.

Patented Oct. 9, 1917.

Original application filed November 29, 1912, Serial No. 734,095. Divided and this application filed January 22, 1916. Serial No. 73,669.

To all whom it may concern:

Be it known that I, ERASTUS E. WINKLEY, a citizen of the United States, residing at Lynn, in the county of Essex and State of Massachusetts, have invented certain new and useful Improvements in Machines for Operating on Shoe-Welts; and I do hereby declare the following to be a full, clear, and exact description of the invention, such as will enable others skilled in the art to which it appertains to make and use the same.

This invention relates to machines for preparing welted unsoled shoes for the sole laying operation. The operations required on the shoe at this time include the leveling or "butting" of the welt ends and the securing of the butted welt ends to the insole, usually by tacks. The present invention relates particularly to mechanisms for performing the welt butting operation, and to welt butting mechanisms of the general type illustrated in my prior Letters Patent of the United States No. 1,029,837, dated June 18, 1912. The present application is a division of my pending application Serial No. 734,095, filed November 29, 1912, which shows a machine that both butts the welt ends and secures the ends to the insole by means of tacks. The claims of this parent case, however, are directed to the tacking mechanism, while the present application is concerned with the welt butting mechanism.

One object of the present invention is to simplify and improve the type of welt butting mechanism used in my prior machine to enable it to operate at a greater speed than has heretofore been practicable, while at the same time performing the desired operations in a more efficient manner and with less expenditure of power. It is a further object of the invention to devise a mechanism of this type which will be capable of operating on all sizes and styles of shoes without preliminary adjustment, and to simplify and improve the construction and operation of the devices for positioning and supporting the shoe for the welt butting operation.

With these and other objects in view, the invention resides in certain devices, combinations and arrangements of parts, as hereinafter described, possessing advantages which will be obvious to those skilled

in this art, and the novel features of which will be pointed out in the appended claims. 55

The various features of the invention will be readily understood from the following description, reference being made to the accompanying drawings, which illustrate the preferred embodiment of the invention, and 60 in which—

Figure 1 is a front elevation showing the welt butting instrumentalities of the machine shown in my application above designated, certain parts of the machine both 65 above and below these instrumentalities being omitted;

Fig. 2 is a rear elevation of the parts illustrated in Fig. 1;

Fig. 3 is a side elevation of the parts 70 shown in Figs. 1 and 2;

Fig. 4 is a cross sectional view, partly in elevation, on the line 4—4, Fig. 3;

Fig. 5 is a sectional view on the line 5—5, Fig. 3, certain parts, however, being shown 75 in plan;

Fig. 6 is a vertical, sectional view on the line 6—6, Fig. 5;

Fig. 7 is a detailed plan view of the welt rests showing them in the proper relationship to a shoe for the purposes of the welt butting operation; 80

Fig. 8 is a detail view in front elevation and on a large scale of certain parts of the welt butting mechanism; 85

Fig. 9 is a perspective view, partly in section, of the heel portion of a welted shoe ready for the welt butting operation to be performed on it; and

Fig. 10 is a cross sectional view of a shoe 90 with the welt rests of the machine supporting the ends of the welt in readiness for the butting operation to be performed.

The illustrated embodiment of the invention shows a machine adapted to butt both 95 ends of the welt at the same time, and there is provided, therefore, a pair of welt rests 1 and 2, and a pair of welt cutters 3 and 4. The rest 1 and cutter 3 are carried by a head 5 which is mounted at the right of the machine to swing in a horizontal plane on a vertical pin 6 (Fig. 5) carried by a horizontal plate 7 (Fig. 1) bolted to the top of column 8. The rest 2 and a cutter 4 are also mounted in a head 9 which is pivotally 100 mounted at the left of the machine on a ver-

tical pin 10 (Fig. 5) carried by the plate 7. The heads 5 and 9 are mounted for simultaneous movement toward each other in order to position the rests beneath the loose ends 5 of the welt at the opposite sides of a welted, unsoled shoe and for simultaneous separating movement to permit the unobstructed removal and insertion of the shoe out of and into operative position between the heads. 10 To this end the head 5 carries a segment 11 which is engaged by a segment 12 (Fig. 3) formed on the vertical arm of a bell crank lever 13 pivoted on a horizontal pin 14 carried by a plate 15 rising from the right side 15 of the plate 7 (see Fig. 3). The horizontal arm of the bell crank lever 13 is pivotally connected to a vertical rod 16 (Fig. 3), connected in turn to one end of a bar 17 (Figs. 1 and 2) carried upon the upper end of a 20 vertical rod 18 which is connected at its lower end with a treadle 19 pivotally mounted on the base of the column 8. The bar 17 carries at its other end a second vertical rod 20 (Fig. 2) which is pivotally connected to 25 the horizontal arm of a bell crank lever 21 pivoted on a plate 22 rising from the left side of the plate 7. The vertical arm of the bell crank lever 21 has formed thereon a segment 23 which meshes with a segment 24 30 carried on the head 9. To hold the heads 5 and 9 normally separated the treadle 19 is connected to the column 8 by a coiled spring 25 (Fig. 2). With this construction a depression of the treadle causes the heads 5 35 and 9 to close and the welt rests 1 and 2 to engage in the welt crease and thus grip and hold a shoe in position between the heads.

In order to permit the ready removal, insertion and adjustment of the cutters 3 and 4 the shank of each of the cutters is mounted in a clamp 26 (Figs. 3 and 6) formed by a split cutter block 27. The cutter block 27 is adjustable mounted in an inclined guide-way 28 (Fig. 8) formed in a carrier 29. The members of the cutting block are moved to clamp the shank of the cutter, and the block is held in adjusted position on the carrier, by a clamping screw 30 having a shank 50 which passes through a slot formed in the block 27 and is threaded into the carrier and has a head which is held within a recess formed for its reception in the front member of the block 27. Each of the welt rests 55 1 and 2 is provided with a body portion 31 (Figs. 6 and 7) dove-tailed into the heads and secured therein by a screw 32. These rests each comprise a guard 33 (Fig. 7) arranged to extend in a horizontal plane beneath the loose ends of the welt over the marginal portion of the heel seat of the shoe, and an inclined wing 34 having its lateral edge arranged to engage the stitches of the insole in the welt crease and its upper face roughened to hold the welt. 60 65

In order to butt the ends of the welt the cutters are first lowered from the position of Fig. 6 until their cutting edges engage the upper surface of that portion of the welt supported by the inclined wings 34 of the 70 welt rests, and are then actuated rearwardly in the plane of the guards 33. This operation produces the desired bevel on the welt ends. With this construction the edge indicated at 35 (Fig. 7) at the line of juncture 75 between the wing 34 and guard 33, acts as a blade coöperating with the cutter in shearing the waste piece from the welt.

Advantage is taken of the well defined edge 35 between the roughened wing 34 and 80 the smooth guard 33 to aid the operative in positioning the shoe for the welt butting operation. To this end the insole of the shoe may be provided with a mark 36 (Fig. 7) at some time before the shoe is brought 85 to the machine, to indicate the proper line of termination of the butted ends of the welt. By registering this mark with the edges 35 the proper position of the shoe 90 relatively to the welt butting instrumentalities is insured without the use of gages and the judgment of the operative is not depended upon.

In order to lower the cutters into their operating plane the rear end of the carriers 95 for the cutters 3 and 4 are secured to pivot pins 38 and 39 (Figs. 5 and 6) journaled in lugs 40 and 41 carried respectively by horizontal slides 42 and 43. These slides are mounted to slide on the heads 5 and 9 100 beneath gibs 44 secured to the heads. To raise and lower the carriers 29 about their pivots 38 and 39 each of the carriers is provided at its forward end with a guideway 45 (Figs. 3 and 6) which slidably embraces a 105 square sleeve 46 loosely mounted on a horizontal rod 47, the opposite ends of which are secured to oblong blocks 48 (Fig. 3) mounted to slide in vertical slots 49 formed in the vertical side plates 15 and 22. The 110 sleeves 46 are held from movement longitudinally of the rod 47 by being each interposed between a boss having connected thereto a bearing plate 50 (Fig. 5) arranged to slide in a slot on the adjacent vertical 115 plate, and a central sleeve 51 on the rod 47. The sleeve 51 is provided with a pair of arms 52 pivoted on a floating rod 53 (Fig. 3) supported by a yoke frame 54 (Fig. 1) which is pivoted on a horizontal rod 55 120 carried by the vertical plates 15 and 22. The rod 53 also loosely carries the forward ends of a pair of links 56 which are pivoted at their rear ends at the opposite sides of a yoke frame 57 (Figs. 3 and 4) pivotally 125 mounted on a horizontal rod 58 carried by the plates 15 and 22. One of the arms of the frame 57 carries a roll 59 which engages a peripheral groove 60 (Fig. 3) formed in a cam cylinder 61 on a shaft 62 journaled at 130

its front end in a bearing 63 (Fig. 3) and at its rear end in a bearing carried by the back plate 65 rising from the plate 7. From the above description it will be seen that 5 the forward end of the welt butting cutter carriers 29 are hung, by their guideways 45, from a pivotal link connection in the form of a toggle, the upper arm of which is formed by the yoke frame 54 and the lower 10 arm of which is formed by the sleeve 51 and its arms 52. The floating rod 53 forms the knuckle of the toggle and power is applied thereto by the cam grooves 60, through the yoke frame 57 and links 56, to make 15 and break the toggle. When the links 56 are drawn rearwardly by the cam the toggle is broken, as shown in Fig. 3, the cutter carriers 29 are raised about their pivots 38 and 39, and the cutters are held above the 20 welt rests. This is the location of the cutter carriers while the shoe is being positioned. On starting the machine the cam moves the links 56 forward thus straightening the toggle and lowering the cutters to welt butting 25 position.

After the cutters are lowered into their operating plane they are actuated rearwardly to butt the welt. To this end the slides 42 and 43 are pivotally connected by 30 means of links 66 and 67 (Fig. 5) to a central slide 68 mounted on the plate 7 beneath gibs 69. The slide 68 carries a roll 70 which engages a peripheral groove 71 formed in a cam cylinder 72^a on the shaft 7. Thus after the cutters have been lowered by the straightening of the toggle and are held rigidly in their lowered position by a dwell in the cam 60, the cam 71 operates 35 through the slides 42, 43 and 68 to draw 40 the carriers rearwardly, the carrier guideways 45 permitting such movement, and the knives 3 and 4 are thus drawn through the welt to sever the welt ends. Each cutter carrier is guided in its rearward movement 45 by a rib 29^a, on the head beneath it, which is embraced by depending wings 29^b on the carrier (Figs. 5, 6 and 8). This construction also insures that the carriers 29 move inward and outward with the heads 5 and 9. 50 During this movement they slide longitudinally on the squared sleeves 46.

The shaft 62 is driven during the operation of the machine from a pulley 137 (Fig. 3) through a "Horton" clutch the roll carrier 55 of which is indicated generally at 138, 138^a, the sleeve within it being splined to the shaft 62. This clutch is controlled manually by the operative to start the machine but is automatically controlled upon the 60 completion of one revolution of the shaft 62 to stop the machine. The roll carrier 138 is provided with the usual lug 139 which normally engages a spring pressed bunter 140 (Fig. 2) to release the shaft 62. The 65 bunter 140 is mounted in a chamber formed

in an arm 142 which is pivotally mounted on a pin 143 secured to the back plate 65 so that the bunter can be withdrawn from engagement with the lug. The pin 143 also carries loosely a dog 144 arranged to engage 70 a lug 144^a on the sleeve 138^a, facing oppositely to the lug 139, and hold the shaft in an invariable position when it is stationary to insure a uniform starting of the cycle of operations of the machine. The bunter 75 140 and dog 144 are withdrawn from the lugs 139 and 144^a, to permit the shaft to be driven by the driving pulley 137, by connections from a handle 145 (Fig. 3) located, in a convenient position for manipulation 80 by the operative, at the front of the machine. To this end the arm 142 carries a pin which is normally engaged by a hook 147 (Fig. 2) pivotally mounted on a slide 148 mounted to slide vertically, beneath a plate 85 149, in a bracket 150 carried by the plate 7. The lower end of the slide 148 is connected by a short link 151 to an arm 152 (Fig. 3) projecting from a rock shaft 153 journaled in a bracket 154 depending from the plate 90 7. The rock shaft 153 also carries a forwardly extending rod 155 which supports the handle 145. When the operative raises the handle 145 the slide 148 is lowered which through the hook and pin connection rocks 95 the arm 142 to remove the bunter 140 from its lug 139. To simultaneously remove the dog 144 from its lug 144^a the arm 142 is provided with a pin 156 which when the arm 142 is rocked in the manner described 100 105 engages a tail 157 on the dog 144 and rocks it downwardly about the pin 143. This permits the springs of the Horton clutch to rotate the roll carrier 138 and grip the sleeve 138^a to turn the shaft 62. While the 105 clutch is in operating position the lugs 139 and 144^a lie approximately side by side.

In order to immediately return the bunter 140 to a position where it may reengage its lug 139 and stop the rotation of the shaft 110 62 at the completion of a single revolution, the plate 149 carries a stop 158 which strikes a tail 159 on the hook 147 when the latter is lowered and rocks the hook 147 about its pivotal connection with the slide 148 thereby 115 causing the hook to be disengaged from the pin on the arm 142. The operative now releases the handle 145 which has sufficient weight, through the connections described, to elevate the slide 148. As the slide 148 120 rises its upper end strikes the underside of the arm 142 and elevates the bunter 140 into the path of movement of its lug 139. The dog 144 is yieldingly supported on the arm 142 by means of a spring pressed plunger 125 160 which holds the dog in the path of movement of its lug 144^a. The hook 147 is actuated to again snap over the pin on the arm 142 by a spring pressed plunger 161 carried by the slide 148. The engagement 130

of the lug 139 with the bunter 140 arrests the rotary movement of the roll carrier 138, the continued movement of the sleeve 138^a frees the Horton clutch rolls, thus freeing 5 the roll carrier from the shaft 62, and also carries the lug 144^a past the end of the dog 144 so that when the movement of the sleeve is checked by the roll springs, its return is prevented by the engagement of the lug 10 144^a with the end of the dog 144.

For convenience in delineation, the machine has been illustrated with the parts all in a neutral position, that is, with the heads 5 and 9 carrying the welt rests and cutters 15 parallel to each other (see Figs. 1 and 5) and consequently the segments 11 and 24 in central position. It will be clear, however, from the foregoing description, that when the machine is at rest, ready for the 20 insertion of a shoe, the heads 5 and 9 are at an angle to each other and in their outermost positions permitted by the upward movement of the treadle rod 18, determined by the engagement of the treadle with a suitable stop. At this time the cutters are raised 25 as in Figs. 1 and 3 with the toggle broken.

In operating the machine illustrated in the drawings the operative inserts a welted, unsoled shoe between the heads 5 and 9 and then depresses the treadle 19 to bring the 30 welt rests into position in the welt creases at the opposite sides of the shoe. As the heads swing in, the operative manipulates the shoe until the mark 36 on the insole, if 35 it be marked, registers with the edges 35 on the welt rests. After the welt rests have engaged the shoe the operative may, by applying further pressure to the treadle, cause the welt rests to tighten the materials of 40 the shoe at the welt butting points if considered desirable. That is, the upper sometimes bulges away from the opposite sides of the last, leaving spaces as indicated at e, Fig. 9, and the pressure of the welt rests 45 1 and 2 against the shoe may be made sufficient to force the stock over the margins of the insole and close up these spaces, as indicated in Fig. 10. This is particularly advantageous, of course, where this mechanism 50 is to be used in connection with a tacking mechanism which will insert tacks in the shoe at the proper points to retain it in this position.

As soon as the shoe has been positioned 55 properly the operative raises the handle 145 thus throwing in the "Horton" clutch 138, 138^a. The first movement of the machine is the lowering of the cutters into the plane of the guards 33 of the welt rests. 60 The cutters are then moved longitudinally of the shoe to cut off or butt the ends of the welt. If a tacking mechanism is used in the machine (as in the machine shown in the parent application), this mechanism 65 then is operated to drive the required num-

ber of tacks into the butted welt ends, securing them to the insole of the shoe.

The cutters are next returned to the position indicated in Fig. 3 and the clutch is thrown out, thus stopping the machine. 70 The operative now removes his foot from the treadle to permit the heads to separate, and then removes the shoe from the machine. As soon as the handle 145 is released, the hook 147 reengages the pin carried by 75 the arm 142 and the clutch controlling mechanism is again so connected that the machine may be started by another upward movement of the handle.

It will be clear from the foregoing description that some of the features of the invention, as, for instance, the welt butting knife operating mechanism, are not limited to use in a machine in which both ends of the welt are butted in one operation, as they 80 are equally useful in a machine for butting the welt ends singly, and it will be further understood that the invention is not limited to the conjoint use of all the illustrated devices and mechanisms in a single machine. 85

It will be clear to those skilled in this class of machines and with the general objects of the present invention in view, that changes may be made in the details of structure, the described and illustrated embodiment thereof being intended as an exploitation 90 of its underlying essentials, the features whereof are definitely stated in their true scope in the claims herewith presented.

What is claimed as new is:— 100

1. A machine for operating on the welt of a welted unsoled shoe, having, in combination, a welt rest, a welt butting cutter, a slide, a cutter carrier pivotally connected thereto, means for actuating the slide to operate the cutter, and separate means for moving the carrier from and toward the welt rest about its pivotal connection with the slide, substantially as described. 105

2. A machine for operating on the welt of a welted unsoled shoe, having, in combination, a welt rest, a welt butting cutter, a slide, a cutter carrier pivotally connected thereto, means for moving the carrier from and toward the welt rest about its pivotal connection with the slide including a toggle, 110 and a cam for breaking and making the toggle, substantially as described. 115

3. A machine for operating on the welt of a welted unsoled shoe, having, in combination, a welt rest, a welt butting cutter, a horizontal slide, a cutter carrier pivoted thereto, means for raising and lowering the carrier from and toward the welt rest about its pivotal connection with the slide, and 120 means for reciprocating the slide to operate the cutter, substantially as described. 125

4. A machine for operating on the welt of a welted unsoled shoe, having, in combination, a welt rest, a pivoted cutter carrier 130

supporting a cutter opposite the welt rest, a pivotal link connection for supporting the forward end of the cutter carrier, constructed and arranged for raising and lowering the cutter toward and from the welt rest to position the cutter for butting, and means for reciprocating the cutter carrier to butt the welt, substantially as described.

5. A machine for operating on the welt 10 of a welted, unsoled shoe, having, in combination, a welt rest, a welt butting cutter slide, a cutter carrier supporting a cutter operated by the slide, means for reciprocating the slide to butt the welt, and separate 15 means for raising and lowering the carrier toward and from the welt rest to position the cutter for butting the welt, substantially as described.

6. A machine for operating on the welt 20 of a welted, unsoled shoe, having, in combination, a welt rest, a welt butting cutter, means for actuating the cutter to butt the welt, and separate means to move the cutter toward and from the welt rest into and out 25 of cutting position, substantially as described.

7. A machine for operating on the welt 30 of a welted, unsoled shoe, having, in combination, a cutter carrier having a welt butting cutter, a toggle mechanism for holding said carrier away from the welt, means to make and break the toggle to move the cutter into and out of cutting position, and means to actuate the carrier to cause the cutter to butt 35 the welt, substantially as described.

8. A machine for operating on the welt 40 of a welted, unsoled shoe, having, in combination, a cutter carrier having a welt butting cutter normally held removed from the welt, means for moving the cutter toward and from the welt into and out of cutting position, and means to reciprocate the carrier after the cutter has been brought into engagement with the welt to cause the cutter 45 to butt the welt, substantially as described.

9. A machine for operating on the welt of a welted, unsoled shoe, having, in combi-

nation, a cutter carrier having a welt butting cutter, a toggle mechanism, means to operate the toggle to hold the cutter in welt butting 50 position, and means to actuate the carrier relatively to the toggle to cause the cutter to butt the welt, substantially as described.

10. A machine for operating on the welt of a welted, unsoled shoe, having, in combination, a cutter carrier having a welt butting cutter, means to reciprocate said carrier to cause the cutter to butt the welt, a toggle mechanism to hold the cutter in welt cutting position during its reciprocation, and means 60 to break the toggle to remove the cutter from the welt at the completion of the welt butting operation, substantially as described.

11. A machine for operating on the welt 65 of a welted, unsoled shoe, having, in combination, a cutter carrier having a welt butting cutter, a toggle mechanism to move the carrier toward and from the shoe, a cam to operate the toggle, a reciprocating slide to move the carrier longitudinally of the welt, 70 and a cam for operating said slide, substantially as described.

12. A machine for operating on the welt of a welted, unsoled shoe, having, in combination, a pair of cutter carriers each having 75 a welt butting cutter, means to reciprocate said carriers longitudinally of the shoe to butt the two welt ends, means to move said carriers relatively to each other laterally, and a single means engaging both carriers 80 to move the cutters into and out of welt butting position, substantially as described.

13. A machine for operating on shoes, having, in combination, a pair of longitudinally and laterally movable cutter carriers 85 each having a welt butting cutter, a single means to raise and lower the cutters out of and into welt butting position, and operative connections between each of said carriers and said means permitting both longitudinal 90 and lateral movement of the carriers relatively to the shoe, substantially as described.

ERASTUS E. WINKLEY.
